JERSEY, A CORPORATION OF NEW JERSEY.

BOBBIN CASE AND TENSION.

1,157,245.

Specification of Letters Patent. Patented Oct. 19, 1915.

Application filed April 28, 1910. Serial No. 558,204.

To all whom it may concern:

Be it known that we, CHARLES LOUIS MILLER and FRANK BARR FREEMAN, citizens of the United States, residing at Norwood and Cincinnati, respectively, in the county of Hamilton and State of Ohio, have invented 5 certain new and useful Improvements in Bobbin Cases and Tensions; and we do hereby declare the following to be a full, clear, 10 and exact description of the invention, such as will enable others skilled in the art to which it appertains to make and use the same.

This invention relates to certain new and 15 useful improvements in bobbin cases, and more particularly to the tension devices applied to bobbin cases which are used in the shuttles of lockstitch shoe sewing machines.

One object of the invention is to provide 20 an improved tension device which may also be utilized to hold the bobbin in its operative position in the bobbin casing.

A further object of the invention is to provide means for varying the amount of the 25 tension upon the thread.

With the above objects in view one feature of the invention comprises means for frictionally retarding the rotation of the bobbin, which in consequence produces a tension 30 upon the thread as it is drawn from the bobbin.

The preferred means for retarding the rotation of the bobbin comprise a stationary member supported by the head of a yieldable bolt, which bolt extends through the center of the bobbin and has a constant tendency 35 to move in a direction to force the stationary member against the surface of the bobbin, and owing to the engagement between the stationary member and the bobbin the rotation of the latter will be frictionally retarded. The preferred means for yieldably supporting the bolt comprises a coiled spring surrounding the bolt.

Means is also provided for normally locking 45 the bolt against rotation relatively to the bobbin case and in accordance with a further feature of the invention the locking means is capable of disengagement upon a slight movement of the bolt in a lengthwise direction, enabling the bolt to be rotated to adjust the tension of the coiled spring and consequently vary the pressure with which

the stationary member bears upon the surface of the bobbin.

These and other features of the invention, including certain details of construction and combinations of parts, will be further explained in the following description and then pointed out in the appended claims.

The various features of the invention will be best understood from a description of the preferred embodiment thereof illustrated in the accompanying drawings, in which—

Figure 1 represents an elevation of the improved device applied to the shuttle of a typical lockstitch sewing machine; Fig. 2 represents an enlarged sectional elevation of the bobbin case and bobbin mounted therein, taken upon the line A—A of Fig. 1; and Fig. 3 is a detail showing the engagement of the stationary member and supporting bolt.

In the embodiment of the invention illustrated in the drawings, the bobbin case 1 is shown as mounted in one of the well known types of oscillating shuttle 2, which in turn is mounted in a shuttle race 3 as usual. The bobbin case 1 and shuttle 2 are held in proper operative position by the usual bobbin holding arm 4. The above described features and arrangement thereof are all old and well known in the art, and are only briefly described in consequence thereof.

In order that the bobbin may readily be inserted in operative position, the bobbin case 1 is open at one side. The bobbin 5 is rotatively mounted in the case by being journaled upon a hollow stud 6 which projects inwardly from the inner face of the bobbin case. A pin or bolt 7 is mounted within the hollow stud 6 and is provided with a head 8 which projects beyond the outer face of the bobbin. The opposite end of the bolt 7 is threaded at 9.

It is preferred to secure a tension upon the thread, by retarding the rotation of the bobbin rather than by providing a separate tension device upon the bobbin case, which engages the thread as it leaves the bobbin.

The improved means provided for retarding the rotation of the bobbin, and which at the same time hold it in operative position in the bobbin case, comprise a flat disk 10 adapted to engage one face of the bobbin. This disk is provided with a radial slot 11 extending from the periphery to the center

of the same, the sides of which are preferably adapted to engage a transverse slot, or slots, 12 formed in the shank of the bolt adjacent to the bolt head 8, by which means the disk is supported on the bolt and locked against rotation relatively thereto. The invention, however, as defined by the claims is not limited to this form of control but is of sufficient breadth to include a structure in which the slots are formed in the periphery of the bolt head 8 and the disk mounted thereon. The disk 10 is pressed against the outer face of the bobbin 5 by yieldingly mounting the bolt 7 in such a manner that there is a constant tendency for the bolt to move in a lengthwise direction and draw the head 8 toward the bobbin. The above result is obtained by mounting a coiled spring 12^a about the bolt 7 within the hollow stud 6. The coiled spring 12^a bears at one end against an inwardly projecting flange 13 formed upon the hollow stud at one end thereof and at the other end against a square nut 14 threaded on the bolt 7 and seated in a square hole 15 in the closed side of the bobbin case.

In order that the nut 14 cannot be accidentally displaced, a lock nut 16 is threaded upon the outer end of the bolt 7 engaging the nut 14.

It is convenient under certain conditions to vary the tension on the thread. This result is obtained, in the illustrated form of the invention, by varying the frictional pressure of the disk 10 upon the bobbin 5. Rotation of the bolt 7 is normally prevented by locking it to the hollow stud 6 by means of a key 17 and keyway 18 upon the bolt and inner portion of the stud respectively. It will be noted that the bolt is keyed to the stud adjacent to the outer end of the stud and, therefore, a slight movement of the bolt in a lengthwise direction will disengage the locking means. The degree of pressure which the disk 10 exerts upon the bobbin may be adjusted by varying the tension of the spring 12. This is accomplished by first pressing upon the lower end of the bolt and thus moving the same outwardly against the action of the spring 12 until the locking means are disengaged and then rotating the bolt in either direction which rotation, owing to the fact that the nut 14 is held against rotation in the casing, will cause the bolt to be screwed into the nut and by thus varying the distance between the nut and the flange 13 the tension of the spring 12 is increased or diminished according to the direction in which the bolt is rotated.

Machines of this type run at a comparatively high speed, and due to the constant movement of the bobbin case and shuttle there is a tendency for the disk 10 to be displaced from its proper position. To avoid this the outer face of the disk is countersunk

or recessed at 19 (see dotted lines Fig. 2), the head of the bolt 7 being seated in this recess.

While the particulars described are well suited to one mechanical form of the invention, it is not to be understood that these particulars are essential since they may be variously modified within the skill of the artisan without departing from the true scope of the actual invention as defined by the claims.

We claim—

1. A shuttle tension device having, in combination, a bobbin case open at one side, a bobbin within the case and having a central aperture extending therethrough, a headed bolt within the aperture, means normally tending to move the bolt in a direction to draw the head within the bobbin, and retarding means held by the bolt in frictional engagement with one face of the bobbin.

2. A shuttle tension device having, in combination, a bobbin case open at one side, a bobbin rotatively mounted therein, a bolt extending through the bobbin and provided with a head projecting beyond the outer surface of the same, a spring coöperating with the bolt and normally tending to move the bolt in a direction to draw the head within the bobbin, and a member detachably mounted on the head of the bolt and frictionally engaging the outer surface of the bobbin.

3. A shuttle tension device having, in combination, a bobbin case open at one side and provided with a hollow centrally arranged stud, a bobbin journaled on said stud, a headed bolt supported within said stud for yielding longitudinal movement, and a retarding member arranged to engage beneath the bolt head whereby the retarding member is held in frictional engagement with one face of the bobbin.

4. A shuttle tension device having, in combination, a bobbin case open at one side, a bobbin rotatably mounted therein, a bolt extending through the center of the bobbin provided with a head projecting beyond the outer surface of the same, means normally tending to move the bolt in a direction to draw the head within the bobbin, and a plate adapted to engage the bobbin beneath the bolt head, the outer face of the plate having a countersunk portion to receive the head of the bolt wherein it is held by the inward movement of the bolt and accidental movement of the plate is avoided.

5. A shuttle tension device having, in combination, a bobbin case open at one side having a centrally arranged hollow stud provided with an inwardly flanged end, a bobbin journaled on said stud, a headed bolt within said stud provided at one end with a squared nut seated within a squared opening within the bobbin case, a coiled spring

within the stud between said nut and flanged end and surrounding the bolt, and a plate arranged to be seated beneath the head of the bolt and held by said spring in frictional contact with one face of the bobbin.

5 6. A shuttle tension device having, in combination, a bobbin case open at one side, a hollow stud, a bobbin journaled upon the said stud within the bobbin case, a bolt extending through the hollow stud provided with a head projecting beyond the outer surface of the bobbin, a coiled spring surrounding the bolt within the stud and normally tending to move the bolt in a direction to draw the head within the bobbin, and means for varying the tension of the spring.

10 7. A shuttle tension device having, in combination, a bobbin case open at one side, a hollow stud, a bobbin journaled upon the stud, a bolt extending through the hollow stud and provided with a head projecting beyond the outer surface of the bobbin, a coil spring surrounding the bolt within the stud and tending to move the bolt in a direction to draw the head within the bobbin, and means for locking the bolt against rotation relatively to the stud and arranged to be disengaged upon a lengthwise movement of the stud.

15 8. A shuttle tension device having, in combination, a bobbin case, a central hollow stud provided with an inwardly projecting flange at its outer end, a bobbin journaled upon the stud within the bobbin case, a bolt mounted within the said stud and provided with a head projecting beyond the outer

surface of the bobbin, a nut on the opposite end of the bolt, and a coiled spring surrounding the bolt within said hollow stud and bearing at one end against the flanged portion of said stud and at the opposite end against the nut, and a plate engaging the head of the bolt and bearing against the bobbin to frictionally engage the same, the bolt normally locked against rotation relatively to the hollow stud but capable of being disengaged upon lengthwise movement of the bolt against the action of the spring whereby the bolt may be rotated and the tension of the spring changed to vary the friction of the plate upon the bobbin.

20 9. In a device of the class described, the combination with a casing having an opening in one side to receive a bobbin, a shaft carried by the opposite side concentric of said opening to receive and carry a bobbin, means mounted on said shaft and extending therefrom toward the edge of the opening to retain the bobbin on the shaft, and spring-pressed means carried by said shaft for drawing said means inward, said shaft being of less length than the bobbin to be used whereby the means for retaining the bobbin on the shaft will bear on the face of the bobbin under the influence of the spring action placing tension on the thread.
